UNITED STATES PATENT OFFICE.

OSCAR ANDERSON, OF CLINTON, ILLINOIS.

RADIATOR CONSTRUCTION.

Application filed August 25, 1921. Serial No. 495,344.

To all whom it may concern:

Be it known that I, OSCAR ANDERSON, a citizen of the United States, and a resident of the city of Clinton, in the county of De Witt and State of Illinois, have invented certain new and useful Improvements in Radiator Construction; and I do hereby declare that the following is a full, clear, and exact description of the same, reference being had to the accompanying drawings, and to the numerals of reference marked thereon, which form a part of this specification.

Considerable difficulty has heretofore been experienced by automobile owners and repair men in connection with leaky and defective radiators, especially those supplied with the cheaper types of cars, it having been found, in many cases, almost impossible to repair a punctured radiator tube without completely rebuilding the radiator, which, of course, was the source of considerable trouble and expense. This, of course, is due to the fact that the top and bottom reservoirs of the radiator are connected by vertical tubes through which the water circulates, and a set of cooling flanges or radiating fins, consisting of a number of longitudinal plates having holes therein through which the tubes pass, are associated with the said vertical tubes, the horizontal plates providing a large cooling or radiating surface.

One of the objects of this invention, is, therefore, to provide an automobile radiator in which the connecting tubes are made in a number of readily detachable banks or sections each consisting of a series of tubes which are easily accessible.

Another object of this invention is to provide a new and improved type of cooling flange or fin which does not extend entirely across a horizontal section of the radiator and which, therefore, will not have to be cut in order to enable a repair man to locate and reach a leaky tube.

A still further object of the invention is to provide a new type of radiator fin which is connected with only one tube or set of tubes and which therefore can be readily disassembled and taken out of the radiator structure.

Other and further objects of this invention will be apparent from the disclosures in the accompanying drawings and specification.

The invention (in a preferred form) is illustrated in the drawings and hereinafter more fully described.

On the drawings:

Figure 1 is a front elevation of my improved type of radiator shown as applied to a well known type of automobile.

Figure 2 is a sectional elevation of the same taken at right angles to Figure 1.

Figure 3 is a detail sectional view taken at right angles to Figure 2.

Figure 4 is a horizontal section taken on the line 4—4 of Figure 3.

Figure 5 is a detail plan view of a portion of the bottom of the upper reservoir.

As shown of the drawings:

The reference numeral 10 indicates an automobile radiator of a common shape and type having my improved tubes and radiating fins incorporated therein. The radiator 10 is mounted in an ordinary manner upon the spring 12 and front axle 14 of the car. This radiator comprises an upper reservoir 16, a lower reservoir 18, and the usual vertical connecting tubes 20, upon which tubes are arranged radiating fins 22 according to my invention. These radiating fins or cooling flanges 22 are bent outwardly and then inwardly in zig-zag form as shown in Figure 3, and at their points of contact with the tubes 20, are bent around into the shape shown at 24 in Figures 3 and 4, in order to form a closer union with the tubes and they may be soldered or brazed to the tubes at these points if desired, in order to form a more perfect heat conducting joint.

At the top of each bank of tubes 20, usually four, in number, is soldered or brazed a perforated plate 26, made of such a length as to extend across the width of the radiator and accommodate the four tubes. Of course, this number may be varied if desired. Each of the plates 26 has a downwardly extending edge 28 adapted to underlap the edge of the adjacent plate, as shown in Figure 3. At the bottom of each set of tubes 20 is fitted a corresponding plate 30, having a similar overlapping edge 32.

The reservoirs 16 and 18 have inwardly extending horizontal end portions 34 and 36 which are adapted to co-act with the plates 26 and 30, in order to form the bottom of the upper reservoir and the top of the lower reservoir respectively. These plates may be attached to each other by any suitable means as by soldering, brazing or the like. It will

be seen from an inspection of Figures 2 and 3, that two corresponding plates 26 and 30 are adapted to accommodate a bank of four tubes, together with the upper and lower plates 26 and 30 and the two cooling flanges 22 form a complete section which is removable as a whole.

The operation is as follows:

Whenever one or several of the tubes 20 become leaky on account of a puncture in the same caused by freezing or otherwise, the section containing the defective tube or tubes can be removed in a very short time by merely passing a hot soldering iron 10 along the joint formed between the overlapping member 28 and the adjacent portion of the plate 26 of the next bank, and around the overlapping joints formed by the offset member 32 lying over the adjacent 15 portion of the next plate 30. After the solder has been loosened along these joints, the entire section can be slidably removed, then the joints between the tubes 20 and the fins 22 can be heated, and the fins removed, 20 thereby making a repair possible with a minimum of trouble and effort.

Also, in the case of only one of the tubes becoming leaky, and especially if the tube is either in the front or the rear of the 30 radiator, and therefore more readily accessible, the entire section need not be removed, but portions of the radiating fins or cooling flanges 22 may be readily loosened by merely touching a soldering iron to the 35 junctures between the semi-circular parts 24 of the radiating fins and the tube 20, at which point they are soldered together. After the solder has been melted away, one 40 set of radiating fins can be readily removed or pushed to one side without disturbing any of the adjacent fins, and upon its removal, the soldering iron may be readily inserted in the space between the tubes especially if the adjacent radiating fins between two sections have both been removed.

It will be seen that herein is provided a radiator for automobiles which can be readily and easily repaired in case of leaks occurring therein, and with a minimum of time, trouble and expense. All that is necessary is a soldering iron whereby the joints in the top and bottom sections are first melted apart, the section removed; then the fins melted off the punctured tube, if necessary, finally the puncture in the tube is repaired and the radiating fins and sections are soldered back again in position completing the job.

I am aware that numerous details of construction may be varied through a wide 60 range without departing from the principles of this invention, and I therefore do not purpose limiting the patent granted otherwise than necessitated by the prior art.

I claim as my invention:

1. A radiator for automobiles including an upper reservoir, a lower reservoir, a plurality of sets of removable plates comprising the bottom and top of the upper and lower reservoirs respectively, a series of 70 vertical circulating tubes connecting each set of removable plates, and a set of removable cooling flanges on each series of tubes, said flanges being arranged so that each series of tubes may be removed independent 75 of the others.

2. An automobile radiator section comprising a top plate, a bottom plate, a series of vertical tubes connecting said plates, and a horizontally corrugated plate on either 80 side of said tubes detachably secured thereto, each corrugated plate having tube contacting portions on one side only.

In testimony whereof I have hereunto subscribed my name in the presence of two subscribing witnesses.

OSCAR ANDERSON.
